UNITED STATES PATENT OFFICE.

ETHAN I. DODDS, OF PITTSBURGH, PENNSYLVANIA, ASSIGNOR TO FLANNERY BOLT COMPANY, OF PITTSBURGH, PENNSYLVANIA.

MEANS FOR TESTING STAY BOLTS FOR BOILERS.

1,414,075.

Specification of Letters Patent. Patented Apr. 25, 1922.

Application filed February 8, 1918. Serial No. 216,020.

To all whom it may concern:

Be it known that I, ETHAN I. DODDS, a citizen of the United States, and a resident of Pittsburgh, in the county of Allegheny and State of Pennsylvania, have invented 5 certain new and useful Improvements in Means for Testing Stay Bolts for Boilers; and I do hereby declare the following to be a full, clear, and exact description of the 10 invention, such as will enable others skilled in the art to which it appertains to make and use the same.

This invention relates to improvements in means for testing stay bolts for boilers, and 15 more particularly for denoting the condition of integrity of a stay-bolt having a tell-tale bore,—one object of the invention being to provide a simple and efficient device which may be readily handled and connected with 20 a suitable fluid pressure apparatus and applied to the tell-tale bore of a bolt, to determine by the application of pressure within the bolt, whether the latter is ruptured.

With this and other objects in view, the 25 invention consists in certain novel features of construction and combinations of parts as hereinafter set forth and pointed out in the claims.

In the accompanying drawings, Figure 1 30 is a sectional view showing an embodiment of my invention, and Figure 2 is a diagrammatical view.

1 represents the head or body portion of the device and is made with a chamber 2. 35 The end of this chambered head is recessed and adapted for the reception of an externally threaded ring 3 which cooperates with the shoulder 4 formed by the recessing of the head, to clamp the peripheral portion of 40 a flexible diaphragm 5. A nozzle 6 passes through the center of the diaphragm 5 and is secured thereto, said nozzle extending through the chamber 2 and projecting forwardly beyond the same. A spider 7 projects forwardly from the ring 3 and is made centrally with a hub 8 which forms a bearing 45 for the forward portion of the nozzle. The nozzle 6 is made somewhat conical at its forward end and provided with a collar 50 9 of rubber or other packing material whereby a tight fit may be effected between said nozzle and the wall of the inner end of the tell-tale bore 10 of a stay bolt 11.

The inner end of the nozzle 6 communicates with a duct 12 in the handle portion 13

of the device and the rear end of the latter is adapted for the reception of a suitable pipe connection 14 with a tank 14^a or other source of fluid pressure supply, a suitable valve being provided for controlling passage 60 of the fluid through the duct 12. Ports 15 are provided whereby fluid under pressure may pass from the duct 12 to the chamber 2 in the head 1.

The head or body portion 1 is provided 65 with a duct 16 communicating at one end with the duct 12 and having its wall at its open end threaded for the reception of a connection 17 leading to a pressure gage 18.

In using the device to test the integrity of 70 a staybolt, the nozzle is applied to the open end of the tell-tale bore of the bolt, and the valve controlling the supply of fluid pressure (either air or liquid) will then be opened. A portion of the fluid flowing 75 through the duct 12 will enter the chamber 2 through the ports 15. The pressure within the chamber 2 will tend to cause relative movement of the nozzle 6 and the body of the device. The operator will resist backward pressure exerted in the chamber 2 and hence the fluid pressure in the chamber 2 will tend to force the diaphragm 5 and nozzle 6 forwardly and cause a tight connection 80 of the forward end of the nozzle with the staybolt to be maintained during the operation of the device. The fluid under pressure will also pass through the nozzle 6 and enter the tell-tale bore of the bolt and the said fluid pressure will also reach the gage 18 85 through the duct 16.

The fluid will be introduced with a predetermined pressure and if such predetermined degree be indicated on the gage, this fact will indicate that the bolt is whole. 95 Should the bolt be ruptured so that the fluid introduced into the tell-tale bore would leak through a crack or fracture, the gage would show a degree of pressure less than the predetermined pressure and the fact of reduced 100 pressure as indicated by the gage would denote the fractured condition of the bolt. It will be apparent also, that the extent of the fracture of the bolt will be approximately 105 equal to the fall below the predetermined pressure, as indicated by the gage, and thus the device will denote, not only the presence of a fracture of the bolt, but also the approximate magnitude of such fracture.

Having fully described my invention what 110

I claim as new and desire to secure by Letters-Patent, is:—

1. A device for testing boiler staybolts having tell-tale bores, comprising a member 5 having a duct, a nozzle slidably mounted in said member and adapted to communicate with said duct, means whereby fluid pressure may be applied to the slideable nozzle to press the same against a staybolt at the open end 10 of the tell-tale bore thereof, and a pressure gage also communicating with said duct.
2. A device for testing boiler staybolts having tell-tale bores, comprising a portable member, a movable nozzle carried by said member, said nozzle having a free end to engage a staybolt at the open end of the tell-tale bore thereof, means for applying fluid pressure to the movable nozzle to press the same against the staybolt, said member 20 provided with means whereby fluid under pressure may pass through said nozzle and into the tell-tale bore of the bolt, and a pressure gage for denoting such pressure.
3. A device for testing boiler staybolts 25 having tell-tale bores, comprising a head having a chamber, a nozzle movably connected with said head and having a free end adapted to engage a stay bolt at the open end of the bore, means whereby fluid under 30 pressure may pass through said nozzle and enter the tell-tale bore of the bolt, means whereby pressure will tend to press the nozzle toward the staybolt and maintain a tight fit between said nozzle and the staybolt, and 35 a pressure gage for denoting the degree of pressure in the tell-tale bore of the bolt.
4. A staybolt testing device, comprising a chambered head, a diaphragm closing the chamber of said head, a nozzle secured to

said diaphragm, said nozzle having a part 40 in the chamber of the head and a part projecting beyond the diaphragm and adapted for application to the tell-tale bore of a stay bolt, means for conveying fluid under pressure to the chamber in the head and to said 45 nozzle, and a pressure gage for denoting the degree of pressure sustained by the stay bolt.

5. A staybolt testing device, comprising a chambered head and a handle portion having a duct communicating with the chamber in 50 the head, a diaphragm closing said chamber, a nozzle secured to and passing through said diaphragm, said nozzle having a part to communicate with the duct in the handle portion and also having a part projecting 55 beyond the diaphragm for application to the tell-tale bore of a stay bolt, and a pressure gage communicating with said duct.

6. A stay bolt testing device, comprising a chambered head and a handle portion having a duct communicating with the chamber in said head, a ring threaded into one end of the chambered head, a diaphragm held in place by said ring, a spider on said ring having a hub, a nozzle passing through and 60 secured to said diaphragm and adapted for application to the tell-tale bore of a stay bolt, said nozzle passing through the hub of said spider, and a pressure gage communicating with the duct in the handle portion. 70

In testimony whereof, I have signed this specification in the presence of two subscribing witnesses.

ETHAN I. DODDS.
